UNITED STATES PATENT OFFICE.

CHARLES L. LATIMER, OF FORT WADSWORTH, NEW YORK.

VALVE-GRINDING TOOL.

1,219,010.

Specification of Letters Patent. Patented Mar. 13, 1917.

Application filed December 12, 1916. Serial No. 136,482.

To all whom it may concern:

Be it known that I, CHARLES L. LATIMER, a citizen of the United States, residing at Fort Wadsworth, in the county of Richmond, State of New York, have invented certain new and useful Improvements in Valve-Grinding Tools; and I do hereby declare the following to be a full, clear, and exact description of the invention, such as 10 will enable others skilled in the art to which it appertains to make and use the same.

This invention is an improvement in valve grinding tools and has particular reference to a tool for grinding valves on their seats.

An object of the invention is to grind valves which are inaccessibly located and provided with openings or grooves for receiving a suitable instrument whereby the valves are turned and in carrying out this object use is made of a valve engaging head having a yieldable centering device carried thereby for properly positioning said head 25 on the valve.

Another object is the provision of novel means for rotating the valve, said means including adjustable bits carried by the valve engaging head and adapted to removably engage the openings or grooves in the valve.

A further object is to provide a tool of this character which is simple in construction, easy to manufacture and effective in carrying out the purpose for which it is 35 designed.

The inventive idea involved is capable of receiving a variety of mechanical expressions, some of which, for the purpose of 40 illustrating the invention, are shown in the accompanying drawing, wherein:

Figure 1 is a side elevation of the tool constructed in accordance with the invention.

Fig. 2 is a vertical central section through the valve engaging head.

Fig. 3 is a bottom plan view of the head.

Fig. 4 is a perspective view of one of the bits employed in connection with the invention.

Fig. 5 is a view similar to Fig. 2 showing another form of the invention.

Fig. 6 is a bottom plan view of Fig. 5.

The accompanying drawing illustrates what are believed to be the preferred forms of the invention and by particular reference

to Figs. 1 to 4 inclusive, it will be seen that the invention comprises an operative crank handle 10, the lower end of which is externally screw threaded as indicated at 11 and 60 provided with a longitudinal bore or opening 12 for a purpose which will appear in the course of the description.

A valve engaging head 13, preferably in the form of a disk, is provided with a centrally located screw threaded socket 14 for receiving therein the lower screw threaded end 11 of the handle 10. The bottom of the socket 14 is provided with a small opening 15 through which extends a centering 70 pin 16 having a head 17 which normally engages the bottom of said socket and is held in position by means of a coil spring 18 mounted in the bore 12 of the handle 10. This centering pin 16 is employed for the 75 purpose of centering the valve engaging head 13 on the valve and in practice, the point of this pin is first engaged with the center of the valve after which pressure is brought to bear on the handle 10 and the 80 valve engaging head brought into contact with the valve at which time the centering pin recedes within the bore 12 against the tension of the spring 18. Suitable fastening means such as the nut 19 may be threaded 85 upon the lower end of the handle 10 and engaged with the adjacent face of the valve engaging head 13 whereby to securely retain the same in position on the handle.

The valve engaging face of the head 13 is 90 preferably provided with diametrically disposed recesses 20 having conical bearing surfaces, the inner ends of said recesses communicating with the openings 21 which communicate with the opposite face of the head 95 13. Mounted in each of the recesses 20 is an adjustable bit 22 having a beveled surface 23 adapted for engagement with the conical surface of the recess, said bit also having a shank 24 which extends through the opening 21 and has its extremity 25 screw threaded to receive thereon the fastening nut 26 which has interposed therebetween and the adjacent face of the head 13 the flexible washers 27 whereby the bit is securely retained in its adjusted positions. The valve engaging face of each bit is preferably circular in formation and is provided adjacent its periphery with a projecting lug or pin 28 which is adapted to engage in one of the 105 openings in the valve after the bit has been adjusted to its proper position. In order to

- facilitate the adjustment of the bit the valve engaging face of the head 13 around the recess 20 is provided with a graduated scale 29 which will enable the operator to make 5 a proper adjustment of the bit before engaging the head with the valve. The engagement of the lugs 28 in the opening of the valve will enable the latter to be rotated so as to grind the same against its seat.
- 10 In Figs. 5 and 6 there is illustrated another form of the invention which is particularly adapted for use in connection with valves having grooves therein, instead of openings. In this instance a bit, generally indicated by the numeral 30, is in the form of a disk 31 having a slot engaging portion 32 extending therefrom and provided with a longitudinal opening 33 for receiving a centering pin 34 which is otherwise mounted in 15 the same manner as previously described. Extending from the edge of the disk 31 at diametrically disposed points are the parallel arms 35 which extend through the recesses 20 and openings 21 in the head 13 and 20 which are screw threaded upon their ends to receive the fastening nuts 36 for securing the bit in position on the head.
- 25 What is claimed is:—
1. A valve grinding tool comprising an operating handle, a valve engaging head carried by said handle, a bit mounted in said head and having a projection for engaging the recess in a valve, and a centering device yieldably mounted in said head.
- 30 2. A valve grinding tool comprising an operating handle, a valve engaging head carried by said handle, a bit mounted in said head and having a projection for engaging the recess in a valve, a centering pin mounted in said head and projecting into said handle, and a spring mounted in said handle
- 35 40

and engaging said pin for yieldably supporting the same in a projected position.

3. A valve grinding tool comprising an operating handle, a valve engaging head carried by said handle, and having oppositely disposed substantially conical recesses and openings communicating therewith, an adjustable bit rotatably mounted in each recess and having a shank extending through the opening which communicates with said recess, means engaging said shank for securing the bit in its adjusted positions, and a projection extending from each bit for engaging an opening in a valve.

4. A valve grinding tool comprising an operating handle, a valve engaging head carried by said handle, and having oppositely disposed substantially conical recesses and openings communicating therewith, an adjustable bit rotatably mounted in each recess and having a shank extending through the opening which communicates with said recess, means engaging said shank for securing the bit in its adjusted positions, a projection extending from each bit for engaging an opening in a valve, and a centering device mounted in said head.

5. A valve grinding tool comprising an operating handle, a valve engaging head carried by said handle, a centering pin mounted in said head and projecting into said handle, and a spring mounted in said handle and engaging said pin for yieldably supporting the same in a projected position.

In testimony whereof, I affix my signature, in the presence of two witnesses.

CHARLES L. LATIMER.
